HEADREST FOR CHAIRS

Clarence G. Maxson, Rochester, N. Y., assignor to
 Ritter Company, Inc., Rochester, N. Y., a corpora-
 tion of Delaware

Application January 27, 1944, Serial No. 519,897

7 Claims. (Cl. 155—173)

1

This invention relates to head rests for operating chairs such, for example, as those employed by dentists, surgeons, and the like, and, more particularly, to mounting means for the spaced pads of such head rests, one object of the invention being to provide an improved mounting for supporting a pad for resiliently flexible movement for conforming its position to the head of an occupant of the chair.

Another object is to provide a mounting of the above character having a more sanitary type of construction by which the pad may be quickly and easily detached and remounted, for cleaning and sterilization.

A further object is to afford such a pad having a simple and practical construction of such a character as to be economical to manufacture, convenient in use for the dentist or surgeon, and comfortable for the occupant of the chair.

To these and other ends the invention resides in certain improvements and combinations of parts, all as will be hereinafter more fully described, the novel features being pointed out in the claims at the end of the specification.

In the drawing:

Fig. 1 is a side elevation of a head rest embodying the present invention;

Fig. 2 is an enlarged view similar to Fig. 1, with some of the parts in section;

Fig. 3 is an enlarged, central, sectional elevation of the parts of the pad mounting shown in Figs. 1 and 2;

Fig. 4 is a reduced top plan view of the parts shown in Fig. 3;

Fig. 5 is a plan view of parts shown in Fig. 4 detached;

Fig. 6 is a side elevation of the shank portion of the head rest pad, showing a spring retaining means, and

Fig. 7 is a view similar to Fig. 6, but at right angles thereto and partly in section.

The invention is embodied, in the present instance, by way of illustration, in a head rest pad of the type shown generally in United States Letters Patent to A. J. May, No. 2,062,592, comprising a head rest bracket arm 10, having a lower end portion 11 adapted for attachment, by any known or suitable means, to the back of a chair. At its upper end, arm 10 is forked to provide oppositely extending branches 12, each terminating in a mounting 13 for a head rest pad, 14. The ends of arms 12 are turned inwardly to suitably incline the pads for receiving and supporting the head of an occupant of the chair, as well understood in the art.

2

The ends of arms 12 are preferably flared outwardly, or enlarged, as at 15, and formed with an annular seat 16 on which is positioned the peripheral portion of a substantially flat spiral metal spring 17. An annular part 18 is arranged to clamp the spring on its seat, having a flange 19 threadedly engaged with the outer wall of the bracket end, as shown.

The spring 17 provides means for flexibly supporting the pad, for which purpose the inner coils of the spring are positioned in a seat or groove 20 in a metal supporting member 21 formed centrally with a cylindrical socket opening 22, as shown.

15 The pad 14 may be constructed of any known or suitable material, such as rubber, plastic composition, or the like, being formed, in the present instance, of a known plastic composition. Fixed to the rear face of the pad, in any suitable manner, is a metal plate 23 from which projects a metal shank 24 having a reduced cylindrical portion 25 of such diameter as to closely but detachably fit within the socket 22 of member 21. Shank portion 25 is slotted inwardly from its end,

25 as at 26, to receive a forked spring clip 27, the central portion of which is formed with oppositely projecting flanges 28 tightly received in corresponding grooves extending laterally from the inner end of slot 26, as shown, to retain the

30 clip in the slot. The angular arms 27 of the clip project somewhat beyond the diameter of the shank for frictionally engaging the side walls of socket 22 to prevent inadvertent detachment of the shank. The spring 17 thus practically forms the sole connection between the outwardly flared end of the bracket and the part 21 for supporting

35 the pad.

It will be apparent from the above construction that a mounting is provided for resiliently supporting each pad for movement normally of its face and to laterally tilted positions, by which the pad is adapted to conform in position to the head of the occupant of the chair and more comfortably and firmly support the same. Each pad

45 is adapted, furthermore, to be easily and quickly detached by an upward pull to withdraw its shank from the socket member carried by the spring, so that the pad may be readily cleaned and sterilized, from time to time, in accordance with sanitary requirements.

The construction comprises metal parts only, of a simple and durable nature, economical to manufacture, convenient in use by the dentist or surgeon, and comfortable and pleasing to the occupant of the chair.

It will thus be seen that the invention accomplishes its objects, and while it has been herein disclosed by reference to details of a preferred embodiment, it is to be understood that such disclosure is intended in an illustrative, rather than a limiting sense, as it is contemplated that various modifications and arrangements of the parts will readily occur to those skilled in the art, within the spirit of the invention and the scope of the appended claims.

I claim:

1. In a head rest for an operating chair, a bracket for said chair having a hollow end, a head rest pad, a substantially spiral metallic spring housed in said bracket end, and means for detachably connecting one end of said spring with said bracket and the other end thereof with said pad, whereby said spring resiliently supports said pad for movement normal to its face and also for limited tilting movement toward any side thereof.
2. In a head rest for an operating chair, a bracket for said chair, a head rest pad member, and a metallic spring member connected to said bracket, one of said members being provided with a socket and the other of said members having a shank portion detachably mounted in said socket to support said pad member for resiliently flexible movement to conform in position to the head of an occupant of the chair and for being detached for sterilization.
3. In a head rest for an operating chair, a bracket for said chair formed with an annular seat, a head rest pad member, a metallic spring member connected to said bracket and connected to and supporting said pad member, one of said members being provided with a socket and the other of said members having a shank portion detachably mounted in said socket for supporting said pad member for resiliently flexible movement to conform in position to the head of an occupant of the chair and for being detached for sterilization, and an annular part threadedly engaged with said bracket for detachably clamping said spring member on said seat.
4. In a head rest for an operating chair, a bracket for said chair formed with an annular groove, a supporting member formed with a groove, a spiral metal spring positioned in the

grooves of said bracket and member, and a head rest pad member, one of said members being formed with a socket and the other of said members having a shank portion detachably mounted in said socket for supporting said pad member for resiliently flexible movement to conform in position to the head of an occupant of the chair and for being detached for sterilization.

5. In a head rest for an operating chair, a bracket for said chair formed with an annular seat, a supporting member formed with an annular seat and having a socket opening therein, a spiral spring positioned in the seats of said bracket and member, an annular part threadedly engaged with said bracket for detachably clamping said spring on the seat thereof, and a head rest pad having a shank detachably mounted in said socket opening for supporting said pad for resiliently flexible movement to conform in position to the head of an occupant of the chair and for being detached for sterilization.

6. In a head rest for an operating chair, a bracket for said chair having an outwardly flared hollow end, a head rest pad having a supporting part detachable therefrom and positioned within said flared bracket end, a substantially flat spiral metallic spring member housed in said flared bracket end, and means for detachably connecting one end of said spring member to said bracket end and the other end thereof to said pad part, whereby said pad is resiliently supported for flexible movement normal to its face and for limited tilting movement toward any side thereof.

7. In a head rest for an operating chair, a bracket for said chair, a head rest pad member, a substantially spiral metallic spring member, and means for detachably connecting one end of said spring member with said bracket and the other end thereof with said pad member, one of said members being provided with a socket and the other of said members having a shank portion detachably mounted in said socket, whereby said pad member is resiliently and detachably supported for movement flexibly normal to its face and in any laterally tilted direction to conform in position to the head of an occupant of a chair and for being detached for sterilization.

CLARENCE G. MAXSON.
